BABY PANTS

Jessie Yohey and Martha Tredway, Reno, Nev.; said Yohey assignor to Tredway

Application October 30, 1950, Serial No. 12,774

Term of patent 14 years

(Cl. D3—17)

To all whom it may concern:

Be it known that I, Jessie Yohey, a citizen of the United States, residing at Reno, Nevada, and I, Martha Tredway, a citizen of the United States, residing at Reno, Nevada, have invented a new, original, and ornamental Design for baby pants, of which the following is a specification, reference being had to the accompanying drawing, forming a part hereof.

Fig. 1 is a plan view of baby pants showing our new design,

Fig. 2 is a front view of the baby pants, shown in Fig. 1 as they appear in wearing position, and Fig. 3 is a rear view thereof.

The dominant feature of our design resides in the combination on the denim baby pants disclosed of the multiple stitched crotch seam, seams depending angularly from the waistband in association with shaped pockets, all as shown.

We claim:

The ornamental design for baby pants substantially as shown and described.

JESSIE YOHEY.
MARTHA TREDWAY.
